UNITED STATES PATENT OFFICE.

FRITZ NOLTE, OF BERLIN, GERMANY, ASSIGNOR TO SIEMENS & HALSKE AKTIENGESELLSCHAFT, OF BERLIN, GERMANY, A CORPORATION OF GERMANY.

ALTERNATING-CURRENT RELAY.

1,319,723.

Specification of Letters Patent.

Patented Oct. 28, 1919.

Application filed April 1, 1916, Serial No. 88,378. Renewed May 21, 1919. Serial No. 298,776.

To all whom it may concern:

Be it known that I, FRITZ NOLTE, a citizen of the German Empire, and residing at Berlin, Germany, have invented certain new and useful Improvements in Alternating-Current Relays, designed to supervise local circuits, of which the following is a specification.

It has heretofore been proposed to use relays, energized by alternating current, for influencing local circuits in the following manner. A local circuit was led over a contact member which was influenced by the armature of a relay and possessed such a little periodicity of vibrations that when the armature vibrated, the contact member was thrown upward and made contact at only relatively great intervals. A complete and constant interruption of the circuit can evidently not be obtained by such an arrangement. Another proposal was to employ several of such contact members, which, when contact is made, are connected in series over parts of the armature and are tuned to various periods, has also not proved entirely satisfactory under all circumstances, because in such an arrangement, although the frequency with which contacts are made while the relay is energized, is very greatly reduced, such contacts are nevertheless possible.

According to the present invention, the circuit to be supervised is carried in series through two or more contact devices which are controlled by the alternating current, so that as long as the latter is flowing, the circuit to be supervised is always interrupted by one or other of the contact devices. Suitable contact devices can be formed by the armatures of two or more polarized relays, which are suspended so as to hang toward one side. The arrangement is such that the one half wave of the alternating current removes the armature of the one relay (or the armatures of a group of relays) from the corresponding fixed or stationary contact; the other half-wave in a similar way removes the armature of the other relay or the armatures of the other group from the corresponding fixed or stationary contacts. Thus the local or supervised circuit is kept open constantly so long as the alternating current is flowing.

One embodiment of the invention is diagrammatically represented by way of ex-

ample in the accompanying drawing, showing one form of the improved alternating current relay.

Referring to the drawing, it will be seen that in series with the alternating current leads L are connected the windings w of two permanent or polarized magnets m_1, m_2 , having a south pole at each lower end and a north pole in the middle at the top, as shown.

The armatures a_1, a_2 of these magnets are suitably pivoted and are controlled by springs a_x or otherwise, so that they can readily oscillate under the action of the variations of magnetic effect due to the exciting alternating current.

The pivots of the tongues or armatures a_1, a_2 are connected with two poles of a source of local current, through a working relay r, and in their position of rest bear against two contacts k connected by a wire z, so that with the armatures in this position, the local circuit is completed.

In the position of rest, viz. with no current in the alternating circuit, the armatures a_1, a_2 which are shown, may be under the influence of springs a_x , lie against different pole-pieces of the relay magnets, and also against the two contacts k of the local circuit, so completing the latter.

As soon, however, as an alternating current flows through the windings w, the one half wave will weaken one of the south poles and strengthen the other, in a similar manner in both magnet arrangements. Thus the armature in contact with the strengthened pole will retain its position, while the other armature will be reversed, so that there is an interruption of the local circuit at the same.

The next half wave will effect a converse strengthening and weakening of the south poles, so that both armatures a_1, a_2 are reversed and the interruption of the circuit takes place at the other armature. As long therefore, as alternating current is flowing, both armatures are actuated synchronously in the same direction and they alternately serve to interrupt the local circuit, so that the relay r can effect the desired operations with certainty.

The same effects can be obtained when individual elements of the relay arrangement are exchanged. For example, one of the magnets may have south polarity imparted

to its armature and north polarity on the contrary to the two free arms, the direction of winding of the alternating current coils being correspondingly reversed. Furthermore, the stationary contacts *k* may be arranged on the same side of the corresponding armatures, if in the one relay magnet, the armature is of south polarity and in the other of north polarity. The pole windings 5 would then be in the same direction.

10 The armatures might, however, be of the same polarity if the windings were arranged to exercise opposite magnetizing effects.

15 In the two latter cases the armatures in the position of rest and with no alternating current flow, assume corresponding positions or incline the same way.

20 The two relay magnets may be united in one. In this case, the U-shaped magnet is widened so that two pole pieces with their windings and two different armatures can be used. Alternatively, one magnet having 25 coils wound in the same direction, can be employed, its two armatures being adapted to co-act with oppositely arranged break contacts.

Having thus described my invention, I claim as new and desire to secure by Letters 30 Patent of the United States:—

35 1. The combination with a circuit to be controlled, of a source of alternating current, permanent relay magnets the windings of which are connected to said source of alternating current so that the poles of each electro-magnet are alternately strengthened and the other weakened by the 40 succeeding half waves of alternating current flowing through the windings, movable contact members closing the circuit to be controlled in their rest position and constituting the armatures of said electro-magnets, the

said armatures being positioned with regard to their contact pieces and the pole pieces of their respective magnets so as to be alternately the ones repelled from their contact pieces and the others attracted toward the same under the magnetic action of the pole pieces influenced by succeeding half waves of alternating current flowing through the windings. 45 50

2. The combination with a circuit to be controlled, of a source of alternating current, two polarized horse shoe relay magnets connected in series with the latter and having pole pieces of the same polarity, movable contact members closing the circuit to be controlled in their position of rest, and constituting the armatures of said electro-magnets, the said armatures being pivoted to the yoke of their respective magnets and biased 60 in their position of rest by a spring toward pole pieces differently influenced by the same half wave of alternating current.

3. An alternating current relay, comprising in combination, an alternating current 65 circuit, a circuit to be controlled by said alternating current circuit, permanent magnets having coiled portions of said alternating current circuit about their polarized ends, vibratile armatures for said magnets 70 connected in series with and forming part of the circuit to be controlled, which armatures in their normal position close said circuit to be controlled, but upon the flow of alternating current through the alternating 75 current circuit, serve to break said circuit to be controlled and maintain it in open condition, while alternating current is flowing, substantially as set forth.

Signed this 9th day of February, 1916. 80

FRITZ NOLTE.
